UNITED STATES PATENT OFFICE.

FRANZ PUENING, OF PITTSBURGH, PENNSYLVANIA.

APPARATUS FOR DISTILLING CARBONACEOUS MATERIALS.

Application filed November 6, 1922. Serial No. 599,178.

This invention relates to the art of distilling carbonaceous material, such as bituminous coal, lignite, shale, peat, or other carbonaceous material which forms coke. An object of the

invention is to provide an efficient furnace construction that permits the distillation of such carbonaceous material at low temperature, in accordance with the principle of low temperature distillation disclosed in one embodiment in my prior application for Letters Patent of the United States Serial No. 535,790, filed February 11, 1922, and in another embodiment in my prior application for Letters Patent of the United States, filed February 11, 1922, Serial No. 535,791. This principle of low temperature distillation involves the bringing of the material to be distilled into direct contact with a solid heat transfer medium previously heated to a temperature great

enough to effect the entire distillation of the material by transfer thereto of part of the heat stored in the heat transfer medium.

In carrying out the distillation there are employed, as the medium for effecting the transfer of the distilling heat to the material to be distilled, heating walls of a substance of high enough heat conductivity to effect a rapid transfer of the distilling heat to the material, for example, bituminous coal. According to the present embodiment of the invention, individual relatively movable refractory heating walls are employed. These heating walls are individually suspended from a carrier, such as the continuous circular carrier disclosed in my co-pending application for Letters Patent of the United States for distillation of carbonaceous materials, executed October 31st, 1922, Serial No. 599,

177, filed November 6, 1922. The carrier is imparted an intermittent motion to move the circular series of heating walls first through a zone in which said walls are subjected to the heating action of hot gases, then to a charging station where the retorting spaces

between the heating walls are individually and successively charged with the carbonaceous material to be coked, then through a zone in which the coking is effected, and finally to a discharging station where the finished

coke is pushed out of the retorting spaces between the heating walls. The charging and discharging operations are conducted during the intervals of rest of the series of heating walls, such intervals of rest alternating with the intervals of movement. The entire operation is controlled automatically so that the heating

up period, charging period, coking period and discharging period follow each other regularly in a continuous cycle. The present invention is embodied, for convenience of description, in a low temperature distillation apparatus of the type above briefly described and involves the employment of individual heating walls relatively movably supported on the carrier in such manner that, during the discharging or pushing operation, each pair of oppositely facing heating walls may be spread apart to increase the lateral distance between them, so that the pushing is effected with great facility and sticking of the coked material to the sides of such walls is avoided.

The present invention comprises the broadly novel feature of moving apart only those heating walls from between which the finished coke is being pushed so that it is not necessary to take care of the accumulative spacing effect that would occur if all the walls were spread apart simultaneously. Consequently, the heating walls may be unlimited in number and, because of the facility in pushing, practically unlimited in size. While herein disclosed in conjunction with a traveling series of walls, the invention in this respect is not so limited but may obviously be applied to a construction involving a series of walls which do not travel, combined with traveling charging and discharging devices.

In addition to the general objects recited above, the invention has for further objects such other improvements and advantages in operation and results as may be found to obtain in the apparatus hereinafter described or claimed.

In the accompanying drawings, forming a part of this specification, and showing for purposes of exemplification, a preferred form and manner in which the invention may be embodied and practiced, but without limiting the claimed invention to such illustrative instance or instances:

Figure 1 is a vertical sectional elevation, taken in a plane parallel with one of the heating walls and through the heating zone or chamber.

Figure 2 is a vertical section taken in a plane similar to Fig. 1, but through the discharging or pusher station.

Figure 3 is a horizontal section through the pusher taken on the line B—B of Fig. 2.

Figure 4 is a vertical section taken transversely through the heating walls on the line A—A of Fig. 2.

Figure 5 is a composite plan and horizontal sectional view of the heating walls.

Figure 6 is a diagrammatic plan view of the drive for the carrier which supports the heating walls.

In its present embodiment, the invention is applied to the low temperature distillation of bituminous coal, for producing coherent coke, such as is available for domestic heating purposes. For convenience, the ensuing description will be confined to this application of the invention. The novel features and improvements of the invention are, however, applicable to the distillation of other carbonaceous material, for example, to any of the other materials hereinabove mentioned; hence, the scope of the invention is not confined to the specific use and specific embodiment herein described as an illustrative example.

Referring to the drawings: There is shown at C a continuous cylindrical chamber having surrounding vertical walls D which may be constructed of any suitable refractory material. The chamber C is constituted of a heating zone H (see Fig. 1) and of a coking zone. Between the heating zone and the coking zone is located the charging station where the preheated heating walls have their intermediate retorting spaces charged with the material to be coked. The discharging or pusher station P (Fig. 2) is located between the coking zone and the heating zone, so that the retorting spaces between the heating walls pass through the pusher station, while moving from the coking zone back into the heating zone. In the heating zone, hot gases may be supplied to and exhausted from the heating walls in either direction through the upper and lower heat ducts G, G'. Provision is made whereby the hot gases in the heating zone are prevented from passing into and commingling with the distillates evolved from the carbonaceous material in the retorts of the coking zone, and also whereby the evolved distillate is prevented from passing into the heating zone. This waste prevention means is fully disclosed in my co-pending application hereinabove mentioned.

The pushing operation, which effects the discharge of the finished coke from the retorting spaces, is accomplished as the retorting spaces are successively moved into position at the pusher station and during the interval of rest of each retorting space when in such position at the pusher station. The heating wall construction by which the pushing operation is greatly facilitated constitutes one of the principal features of the present invention. The heating walls 1 are constituted of elongated relatively thin vertical members preferably, although not necessarily, constructed of tile or brick sections provided with holes for receiving the vertical hanger rods 2. Each heating wall is pro-

vided on its opposite side faces with a recess R extending from top to bottom of the wall and providing with the facing recess of an adjacent heating wall a retorting space or coking chamber S between each pair of adjacent heating walls. The vertical faces V at the ends of the opposite recesses R of each heating wall make contact with the corresponding vertical faces V of adjacent heating walls, as shown in Fig. 5, except those two adjacent heating walls which are spread apart during the pushing of the coke from the retorting space S.

At their upper ends, the vertical hanger rods 2 are flattened out along the major axis of the heating wall so as to fit into the bottom of the recess of the air cooled supporting beam structure 3. This structure is constituted of an inverted U-beam extending beyond the opposite ends of the corresponding heating wall and to the opposite sides of which the several hanger rods 2 are connected by pins 2a. The beam 3 provides a channel a through which cooling gases or other cooling media may be circulated to keep the supporting structure at the top of each heating wall from becoming too hot. Each beam 3 is surrounded by an insulating cover 6 and the latter is covered by an outer metallic covering 5, this structure providing a secure anchorage for the wall supporting hangers 2. The insulating filler 6 prevents the cover 5 from becoming too cool and the beam 3 from becoming too hot. The bottom course of tile of each heating wall is provided with a groove 9a to receive a bar washer 7 before the nut fastenings 8 are screwed onto the lower ends of the hanger rods 2. After the nuts have been applied and the hanger rods tightened up, a filler of insulating material 9 may be plastered into the groove 9a to protect the rods 2 and nuts 8 from heat and also to provide a substantially flush bottom.

The inverted U-beam 3 has its bottom closed by the bottom plate 3a and its ends which extend beyond the opposite ends of the metal cover 5 closed by the footings 21 and 22. U-tubes or pipes 10 and 16 respectively communicate with the opposite ends of the channel a in the beam 3 through the footings 21 and 22 to which said tubes are connected. These tubes extend down through liquid seals provided by the troughs 11 and 12 and have their outer open ends projected above the level of the liquid in the respective seals.

Mounted above the projecting beams 3 of the series of heating walls and secured to a fixed part of the furnace structure is a cover ring or plate 27, to the outer edge of which is secured a depending apron 13 that dips down into the liquid seal 11 at the outside of the free ends of the several U-tubes 10, as shown more particularly in Figs. 1 and 2. Also secured to the outer edge of the supporting ring 27 is an inside annular apron 14

which dips down into the liquid seal 11 along the inside of the free ends of the U-tubes 10. This construction provides a pocket or closed chamber into which cooling air or other cooling gas may be circulated either by being pumped or drawn through the inlet pipe 15. Inasmuch as the air in said pocket has no other means of escape, it must enter the open ends of the U-tubes 10 which communicate with the interior of the pocket and be delivered by said tubes to the cooling channels α of the heating wall supporting beams 3.

Secured to the inner superstructure of the furnace and above the inner ends of the projecting U-beams 3 is an annular ring or supporting plate 28, to the inner edge of which is secured an annular apron 25 that dips down into the liquid seal 12 between the open ends of the several exhaust tubes 16 and the point where said tubes are connected to the respective footings 22, so that the open ends of the tubes are exposed to the atmosphere. Consequently, the cooling gases forced into the channels α from the tubes 10 are free to exhaust into the atmosphere from the open ends of the exhaust tubes 16, with the result that continuous circulation, without leakage, of cooling media is effected through the cooling channels α of each of the heating wall supports, regardless of the fact that the heating walls and their supports have entirely independent mountings and are movable relatively to each other. Outer and inner annular aprons 29 and 30 dip down into the respective liquid seals 11 and 12 and prevent the escape of hot gases or vapors to the atmosphere.

The troughs 11 and 12 constituting the outer and inner liquid seals are made up of structural shapes forming horizontal annular girders to which the outer and inner driven ring gears 17 and 18 are secured. These gears constitute part of the driving mechanism whereby the progressive motion is imparted to the circular series of heating walls. In order to transmit such motion to the walls, circular rails 19 and 20 are supported within the revolving troughs 11 and 12 and are securely attached thereto so as to partake of their motion. These rails 19 and 20 respectively support the footings 21 and 22 of the heating wall supports and through said footings the heating walls are progressively moved in unison with the troughs 11 and 12. The liquid in said troughs serves as a lubricant between the footings 21 and 22 and the driving rails 19 and 20, permitting the footings to slide over the rails when a pair of adjacent heating walls are spread apart during the pushing operation. The troughs 11 and 12 are supported on the stationary rollers 23 which are mounted in the bearings 24 on ledges near the tops of the outer and inner surrounding refractory walls.

The main drive shaft 40 is provided with

outer bevel driving gears 41 and with inner bevel driving gears 42. The outer bevel driving gears 41 mesh with outer bevel gears 43 at the upper ends of the outer vertical driving shafts 44, and the inner bevel gears 42 mesh with inner bevel gears 45 at the tops of the inner vertical driving shafts 46. Secured to the lower ends of the pairs of vertical driving shafts 44 and 46 are spur gears 47 and 48 which mesh respectively with the outer and inner horizontal ring gears 17 and 18. With this construction a four point drive is provided for the series of heating walls and alternate retorts.

In accordance with the invention the spreading apart of the two adjacent heating walls of a pair which is in position at the pusher station is accomplished just prior to the operation of pushing out the coke, but by means controlled and operated by the pusher machine, so that the spacing of the heating walls 1 and the pushing of the coke may be considered as substantially a single operation. Inasmuch as the heating walls are individually supported on the rails 19 and 20, the walls of the pair at the pusher station are free to move or spread apart relatively to each other. The heating walls of the entire series are so arranged that the vertical faces V of all of the walls except the pair at the pusher station are in tight contact with each other, sufficient clearance being allowed to permit the two walls at the pusher station to spread apart during the pushing operation. This clearance is successively acquired by each pair of adjacent heating walls as it comes into position at the pusher station. As shown, the metal covers 5 of the heating walls supports are provided with vertical grooves 32 on their opposite vertical faces and at their opposite ends beyond the ends of the heating walls. The companion grooves of adjacent heating walls register with each other, as shown in Fig. 5, forming short vertical channels for the entry of the spreaders which are attached to and form part of the pusher mechanism. The pusher slides in a casing 33 mounted on the furnace superstructure above a pair of adjacent heating walls in position for pushing. The pusher is constituted of a central vertical ram plate 34 and side spreaders 35 secured to the opposite vertical edges of the ram plate 34. The side spreaders 35 are made laterally somewhat thicker than the ram plate 34 and project below the bottom edge of the ram plate so that they will enter the channels formed by the grooves 32 and spread the opposite heating walls apart before the ram plate enters the top of the retort between said walls to effect the pushing. In order to facilitate the entry of the spreaders 35 into the channels formed by the grooves 32 one edge of each spreader may be inclined or beveled downwardly into a blunt point as shown at 36. When the pusher descends,

during the operation of the machine by mechanism such as is disclosed in my said co-pending application, the adjacent walls of a pair ready for pushing are first spread apart 5 by the spreaders 35 to loosen any adherent coke and then the ram, passing downwardly through the retorting space between said walls pushes the coke into a discharge chute. 37. Discharge of the coke through the chute 10 37 may be facilitated by a rotary discharger 38. After the pusher has reached its normal elevated position, the pair of heating walls which have just been pushed will be left in their spaced or spread apart position. This 15 space, however, will be taken up by the next heating wall which arrives in position for being pushed.

The gases evolved from the material being carbonized flow off through the outlet 88. 20 The invention as hereinabove set forth may be variously embodied within the scope of the claims hereinafter made.

I claim:

1. Apparatus for distilling carbonaceous 23 materials embodying: a rotary carrier; a plurality of heating wall supports mounted on said carrier for movement thereby and relatively movable with respect to each other; heating walls respectively suspended from 30 said supports; the wall supports being respectively provided with cooling channels having connections at one end which sweep through a sealed gas space, during the movement of said carrier, and having connections 35 at the other end leading to the atmosphere for permitting exhaust of the cooling media circulated through said channels; and a vertically movable pusher embodying side spreaders and an intermediate ram plate, 40 the side spreaders extending below the bottom of said ram plate and engaging the heating wall supports in advance of the entry of the ram plate between adjacent heating walls, to spread said walls apart on the carrier during 45 the pushing operation; substantially as specified.

2. Apparatus for distilling carbonaceous materials embodying: a movable carrier; a plurality of heating wall supports mounted 50 on said carrier for movement thereby and relatively movable with respect to each other; heating walls respectively suspended from said supports; the wall supports being respectively provided with cooling channels 55 having connections at one end which sweep through a sealed gas space, during the movement of said carrier, and having connections at the other end leading to the atmosphere for permitting exhaust of the cooling media circulated through said channels; and a vertically movable pusher embodying side 60 spreaders and an intermediate ram plate, the side spreaders extending below the bottom of said ram plate and engaging the heating wall supports in advance of the entry 65

of the ram plate between adjacent heating walls to spread said walls apart on the carrier during the pushing operation; substantially as specified.

3. Apparatus for distilling carbonaceous 70 materials embodying: a rotary carrier; a plurality of heating wall supports mounted on said carrier for movement thereby and relatively movable with respect to each other; heating walls respectively suspended from 75 said supports; and a vertically movable pusher embodying side spreaders and an intermediate ram plate, the side spreaders extending below the bottom of said ram plate and engaging the heating wall supports in advance of the entry of the ram plate between adjacent heating walls, to spread said walls apart on the carrier during the pushing operation; substantially as specified.

4. Apparatus for distilling carbonaceous 80 materials embodying: a movable carrier; a plurality of heating wall supports mounted on said carrier for movement thereby and relatively movable with respect to each other; heating walls respectively suspended from 85 said supports; and a vertically movable pusher embodying side spreaders and an intermediate ram plate, the side spreaders extending below the bottom of said ram plate and engaging the heating wall supports in advance of the entry of the ram plate between adjacent heating walls, to spread said walls apart on the carrier during the pushing operation; substantially as specified.

5. Apparatus for distilling carbonaceous 100 materials embodying: a rotary carrier; a plurality of heating wall supports mounted on said carrier for movement thereby and relatively movable with respect to each other; heating walls respectively suspended from 105 said supports; the wall supports being respectively provided with cooling channels having connections at one end which sweep through a sealed gas space, during the movement of said carrier, and having connections 110 at the other end leading to the atmosphere for permitting exhaust of the cooling media circulated through said channels; substantially as specified.

6. Apparatus for distilling carbonaceous 115 materials embodying: a movable carrier; a plurality of heating wall supports mounted on said carrier for movement thereby and relatively suspended from said supports; the wall supports being respectively provided 120 with cooling channels having connections at one end which sweep through a sealed gas space, during the movement of said carrier, and having connections at the other end leading to the atmosphere for permitting exhaust 125 of the cooling media circulated through said channels; substantially as specified.

7. Apparatus for distilling carbonaceous materials embodying: a rotary carrier; a plurality of relatively movable heating walls 130

- suspended from said carrier; and a vertically movable pusher embodying side spreaders and an intermediate ram plate, the side spreaders extending below the bottom of said 5 ram plate and engaging the heating walls in advance of the entry of the ram plate between adjacent heating walls, to spread said walls apart on the carrier during the pushing operation; substantially as specified.
- 10 8. Apparatus for distilling carbonaceous materials embodying: a movable carrier; a plurality of relatively movable heating walls suspended from said carrier; and a vertically movable pusher embodying side spreaders and an intermediate ram plate, the side spreaders extending below the bottom of said 15 ram plate and engaging the heating walls in advance of the entry of the ram plate between adjacent heating walls, to spread said walls apart on the carrier during the pushing operation; substantially as specified.
9. Apparatus for distilling carbonaceous materials embodying: a rotary carrier; a plurality of relatively movable heating walls suspended from said carrier; and a vertically movable pusher embodying spreader means and ramming means, the spreader means extending below the bottom of said ramming means and engaging the heating walls in advance of the entry of the ramming means between adjacent heating walls, to spread said walls apart on the carrier during the pushing operation; substantially as specified.
10. Apparatus for distilling carbonaceous materials embodying: a movable carrier; a plurality of relatively movable heating walls suspended from said carrier; and a vertically movable pusher embodying spreader means and ramming means, the spreader means extending below the bottom of said ramming means and engaging the heating walls in advance of the entry of the ramming means between adjacent heating walls, to spread said walls apart on the carrier during the pushing operation; substantially as specified.
11. Apparatus for distilling carbonaceous materials embodying: a plurality of relatively movable heating walls; and a pusher mechanism embodying a spreader and a rammer, the spreader engaging the heating walls in advance of the entry of the rammer between adjacent heating walls, to spread said walls apart for the pushing operation; substantially as specified.
12. Apparatus for distilling carbonaceous materials embodying: a plurality of relatively movable heating walls; and a pusher mechanism embodying a rammer and means constrained to spread said walls apart during the pushing operation; substantially as specified.
13. Apparatus for distilling carbonaceous material embodying: a horizontal series of vertical walls arranged side by side and adapted to provide coking spaces between each two contiguous walls of the series, the length of the series being substantially constant from one end to the other thereof, and each of said contiguous walls being movable to and from each other to vary the width of the coking space therebetween; means for spreading apart pairs of contiguous walls of said series; and a rammer operable subsequently to the spreading operation for pushing out residue from between contiguous 75 walls; substantially as specified.
14. In apparatus for coking material in a plurality of narrow chambers, in combination: a series of heating walls arranged side by side and forming chambers between them; means for heating the walls forming the chambers; a charging station for filling the chambers with material to be coked; a discharging station comprising means for subsequently increasing the space between some 80 of the walls to effect discharge of finished coke; and gas collecting means between said charging station and said discharging station for collecting gases from the chambers between said heating walls; said chambers 85 being movable in a cyclic path through said means for heating, past said charging station for filling, through said gas collecting means, and past said discharging station; substantially as specified.
15. In apparatus for coking material in a plurality of narrow chambers, in combination: a series of heating walls arranged side by side and forming chambers between them; means for heating the walls forming the 90 chambers; a charging station for filling the chambers with material to be coked; a discharging station comprising means for subsequently increasing the space between the walls to effect discharge of finished coke; 95 and gas collecting means between said charging station and said discharging station for collecting gases from the chambers between said heating walls; said chambers being movable in a cyclic path through said means for heating, past said charging station for filling, through said gas collecting means, and past said discharging station; substantially as specified.
16. Apparatus for coking material, embodying: a series of walls forming a series of narrow chambers, heating means and a charging station for alternately heating the walls forming the chambers and filling the chambers with material to be coked, combined 100 with a discharging station comprising means for increasing the space between the walls of some of the chambers to effect discharge of the finished coke, said chambers being movable in a cyclic path through the heating 105 means, past the charging station and past said discharging station; substantially as specified.
17. Apparatus for coking material, embodying: a series of walls forming a series of 110

narrow chambers, heating means and a charging station for alternately heating the walls forming the chambers and filling the chambers with material to be coked, combined 5 with a discharging station comprising means for increasing the space between the walls of a pair of the chambers to effect discharge of the finished coke, said chambers being movable in a cyclic path through the heating 10 means, past the charging station and past said discharging station; substantially as specified.

18. In apparatus for coking material in a plurality of narrow chambers formed by 15 heating walls, in combination, means for heating, filling and emptying said chambers consecutively, means for increasing the space between some of the walls just previous to the emptying operation, and means for thereafter 20 restoring the walls of the emptied chamber to their original spacing; substantially as specified.

19. In apparatus for coking material in a plurality of narrow chambers formed by 25 heating walls in combination, means for heating, filling and emptying said chambers consecutively, means for increasing the space between a pair of the walls just previous to the emptying operation, and means for thereafter 30 restoring the walls of the emptied chamber to their original spacing; substantially as specified.

20. In apparatus for coking material in spaces between narrowly spaced heating 35 walls, in combination: a series of walls arranged side by side and forming a retorting space between each two contiguous walls of the series; means for heating the walls forming retorting spaces; a discharging station 40 comprising means for pushing coke from between contiguous spaced walls; gas collecting means between said means for heating and

said discharging station for collecting gases from the retorting spaces between said walls; said walls being movable in a cyclic path, 45 through said means for heating, through said gas collecting means and past said discharging station; means for keeping the space distances between said contiguous walls at constant distances in said apparatus except 50 at said discharging station; means adapted for increasing the space distances between contiguous walls of the series in advance of pushing the coked material therefrom; and means for thereafter restoring the space distances to said constant distances. 55

21. In apparatus for coking material in spaces between narrowly spaced heating walls, in combination: a series of walls arranged side by side and forming a retorting 60 space between each two contiguous walls of the series; means for heating the walls forming retorting spaces; a discharging station for pushing coke from between contiguous spaced walls; gas collecting means between 65 said means for heating and said discharging station for collecting gases from the retorting spaces between said walls; said walls being movable in a cyclic path through said means for heating, through said gas collecting 70 means and past said discharging station; means for keeping the space distances between said contiguous walls at constant distances in said apparatus except at said discharging station; means adapted for increasing the space distances between a pair of contiguous walls of the series in advance of pushing the coked material therefrom; and means for thereafter restoring the space distances to said constant distances. 75

In testimony whereof I have hereunto set my hand.

FRANZ PUENING.
